DISPLAY DEVICE

Robert A. Krauss, 11700 Shore Cliff Lane,
Mequon, Wis.

Filed June 18, 1963, Ser. No. 288,733

2 Claims. (Cl. 40—132)

This invention relates to display devices and has as its purpose to provide an inexpensive attractive display made essentially of relatively stiff paperboard and characterized by the fact that the device may be "knocked down" into a flat condition permitting the same to be stored and shipped flat or, if desired, in a rolled up condition.

It is also the purpose and object of this invention to provide a display device of the character described which is easy to set up and, when set up, is a three-dimensional structure fully self-supporting and stable.

Another object of this invention is to provide a display device having a front indicia-bearing panel and a back panel which may mount an electric bulb socket so oriented that a light bulb screwed into it is located behind the front panel to attractively illuminate the display.

Another object of this invention is to provide a display device of the character described which is characterized by the fact that it has a flat front panel bearing indicia to be displayed, and a bowed rear panel so connected to the front panel that it holds the latter taut.

A still further object of this invention is to provide a display device having the characteristics stated in the directly preceding object, but further characterized by the fact that the bowed back panel may be equipped with an integral bracket-forming portion to thus enable the display device to stand with one of the straight edges of its bowed back panel at the bottom and the other at the top.

A still further object of this invention is to provide a display device with a bowed back panel as aforesaid, and wherein the bowed back panel is adapted to be readily detachably connected to a tubular handle, enabling the display device to be mounted or carried about as a placard.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention, constructed according to the best modes so far devised for the practical application of the principles thereof, and in which:

FIGURE 1 is a perspective view of a display device constructed in accordance with this invention, with a portion thereof broken away to better illustrate the same;

FIGURE 2 is a perspective view showing how the display device of FIGURE 1 may be "knocked down" and disposed in a flat condition to facilitate storage and shipment;

FIGURE 3 is a perspective view of the same display device shown in FIGURES 1 and 2, but showing the same from the back and illustrating the manner in which it is set up for use;

FIGURE 4 is a perspective view illustrating a modified embodiment of this invention, which is characterized by the provision of a bracket integral with the back panel of the display device;

FIGURE 4A is a view on a considerably reduced scale of the display device shown in FIGURE 4, but illustrating the same in its knocked-down flat condition;

FIGURE 4B is a fragmentary perspective view illustrating a modification of part of the display device shown in FIGURE 4;

2

FIGURE 5 is a perspective view taken from the back of still another modified embodiment of the invention;

FIGURE 6 is a perspective view of another form of the invention which adapts the display device for mounting upon a carrying handle, said view being taken from the back;

FIGURE 6A is a view of the display device of FIGURE 6 shown in its flat "knocked-down" condition and without the handle;

FIGURE 7 is an enlarged detail cross-sectional view through the junction of the contiguous edges of the front and back panels, and illustrating one way in which these edges may be separably connected; and

FIGURE 8 is a view similar to FIGURE 7 but illustrating another way of separably connecting the front and rear panels.

Referring now particularly to the accompanying drawings, the numeral 10 represents generally the display device of this invention. As shown in the drawings, the display device may be embodied in various forms, but in all instances it comprises a front panel 11, rear panel means 12, and binding and retaining strips 13 which hold opposite marginal edges of the front panel and of the back panel means together.

Also in all embodiments of the invention illustrated, the distance between the parallel marginal edges of the back panel means is greater than the corresponding distance for the front panel so that when the display device is set up for use, as in FIGURES 1, 4 and 6, the back panel means is bowed and holds the front panel 11 taut. Obviously, of course, the front panel 11 may bear any desired indicia, as suggested in FIGURE 1. Also, as will be readily understood, the front panel can be cut out if desired to create special effects, and to expose portions of the back panel means which in that event would likewise bear indicia to be displayed.

The front panel, and also the back panel means are preferably formed of relatively stiff though reasonably flexible paperboard, and in all forms of the invention with the exception of that illustrated in FIGURE 5, the back panel means, like the front panel, is one single unit or sheet.

In the case of the display device shown in FIGURE 5, the back panel means comprises a pair of complementary panel members 14-14'. The length of each of these panel members from its outer edge which is connected to the front panel to its free inner edge is greater than half the distance between the opposite parallel edges of the front panel. Hence, when the free inner edge portions of the two panel members 14-14' are secured together as shown in FIGURE 5, they form one bowed member which functions in the same manner as the one piece bowed back panels of the other embodiments of the invention. The panel members 14-14' are separably connected by means of tongues 15 and 16, each projecting from one of the members 14-14' and inserted into slits 17 in the other of such members 14-14', and to secure the members against accidental separation, one of the tongues, in this case the tongue 16, is T-shaped.

Another difference between that form of the invention shown in FIGURE 5 and the other illustrated embodiments, resides in the fact that the opposite parallel edges of its back panel means are permanently secured to the parallel edges of the front panel, since by disconnecting the panel members 14-14' from one another, it is possible to knock down the display device into its desired flat condition for storage and shipping.

The binding and retaining strips 13 comprise thin metal bands bent and folded transversely in the nature of a stove pipe seam. As best seen in FIGURES 7 and 8, each band thus has three superimposed sections 19,

20 and 21, the sections 19 and 21 being outermost and the section 20 being the middle section. The sections 19 and 20 are the marginal portions of the band and, of course, the section 21 is formed by the medial portion of the band.

Where the edges of the front and rear panels are to be permanently secured together, as they are in FIGURE 5, and as is the case in one of the edges of each of the other forms of the invention illustrated, the marginal portions of the front and back panels are wrapped around the edge of the middle section 20 and tightly confined between the middle section and the outer section 21.

In all forms of the invention with the exception of that illustrated in FIGURE 5, in order to give the display device its desired knock-down characteristic, one of the two parallel edges of the back panel means must be detachably connected to the adjacent edge of the front panel. For this purpose, the binding and retaining strips 13 and their connections with the panels may be either as shown in FIGURE 7 or as in FIGURE 8. In the first of these two alternates, the marginal edge 23 of the front panel is tightly clamped between the sections 20 and 21 of the band, but some space is left between the section 20 and the rear face of the front panel to accommodate the marginal edge of the back panel when the device is set up for use. Obviously, of course, the free edge of the back panel is simply tucked into this space between the section 20 and the rear face of the front panel.

Where greater facility in setting up the device and added assurance against disassembly is desired, the construction shown in FIGURE 8 may be employed. In this case, a flap 25 is secured in place along with the marginal edge portion 23 of the front panel by tightly squeezing the sections 19, 20 and 21 of the binding and retaining strip together. This flap provides a relatively wide flange overlying the rear face of the front panel and under which the adjacent edge of the back panel is readily inserted when the device is set up for use.

In those forms of the invention shown in FIGURES 1, 2, and 5, the parallel marginal edges which are bound by the binding and retaining strips 13 are upright, but in the forms of the invention shown in FIGURES 4 and 6 these edges are horizontal. In the case of the construction shown in FIGURE 4, the display device is equipped with a bracket 30 to support the same against tipping. This bracket is conveniently formed as an integral part of the back panel by simply cutting slits 31 into the back panel from its free edge toward its permanently bound edge, and by leaving the material between the two slits long enough to extend substantially beyond the free edge of the panel, as shown in FIGURE 4A.

A marginal flap 32 defined from the bracket forming portion 30 by a bend line 33 is tucked into the slot provided by the binding and retaining strip along with the free edge of the back panel, and a second fold line 34 facilitates folding the portion 30 upon itself, as shown in FIGURE 4, to give the supporting bracket its desired shape.

Another way of holding the bracket forming portion 30 in its operative position is illustrated in FIGURE 4B. As here shown, the bracket forming portion 30 is T-shaped so that it has a head 45 on its extremity, the ends of which are notched as at 46 to have interengaging connection with notches 47 in the back panel. When these connections are established—it being understood that there is one at each side of the bracket—the end of the bracket forming portion is securely held against accidental detachment from the back panel.

The structure shown in FIGURE 6 enables the display device to be attached to a handle 35 by which it may be mounted for display or carried about like a placard. To

this end, the back panel has a hole 36 therein and a tongue 37 struck inwardly. The hole 36 is elongated and is so located that upon insertion of the handle 35 which is preferably a paper tube, the handle may be positioned parallel to the flat front panel with its upper open end 38 adjacent to the tongue 37 which is pushed down into the interior of the handle, as shown.

A feature of the display device of this invention is that it lends itself readily to illumination. For this purpose, the back panel has a hole 40 therein into which the socket 41 of an electric lamp may be inserted with the socket facing forwardly so that a bulb 42 screwed into the socket will be located between the front and rear panels.

From the foregoing description taken in connection with the accompanying drawings, it will be apparent to those skilled in this art that this invention provides a display device which, though inexpensively made is extremely attractive when set up for use and has the very desirable attribute of enabling the same to be stored and shipped flat or in a rolled condition.

What is claimed as my invention is:

1. A display device comprising:
  - (A) a front panel of sheet material adapted to bear indicia to be displayed and having opposite parallel edges;
  - (B) a single back panel of substantially resilient sheet material having opposite parallel edges;
  - (C) stiff binding and retaining strips secured to said edges of the front panel and gripping said edges of the back panel;
  - (D) the distance between said opposite parallel edges of the back panel being greater than the corresponding distance for the front panel so that the back panel is bowed and the bowing thereof keeps the front panel stretched taut;
  - (E) one of said binding and retaining strips securing one of said edges of the back panel to the adjacent one of said edges of the front panel, the other of said edges of the back panel being a free edge and being removably held by the adjacent binding and retaining strip so that said free edge of the back panel may be detected from said adjacent binding and retaining strip to enable the back panel to be laid flat upon the front panel and thereby adapt the display device to being stored and shipped flat;
  - (F) said back panel having slits extending inwardly from its free edge toward its secured edge to define a bracket forming portion which extends beyond said free edge of the back panel when the panel is flat;
  - (G) a marginal flap on the outer extremity of said bracket forming portion detachably gripped by that binding and retaining strip which detachably holds the free edge of the back panel;
  - (H) and said bracket forming portion having a fold medially of its ends and parallel with its free edge whereby, when the marginal flap of said bracket forming portion is engaged with the adjacent binding and retaining strip, said bracket forming portion provides a support for the display device enabling the same to be set upon a surface with its front panel substantially upright and its said parallel edges disposed horizontally.
2. A display device comprising:
  - (A) a front panel of sheet material adapted to bear indicia to be displayed and having opposite parallel edges;
  - (B) a single back panel of substantially resilient sheet material having opposite parallel edges;
  - (C) stiff binding and retaining strips secured to said edges of the front panel and gripping said edges of the back panel;
  - (D) the distance between said opposite parallel edges of the back panel being greater than the corresponding distance for the front panel so that the back

- panel is bowed and the bowing thereof keeps the front panel stretched taut;
- (E) one of said binding and retaining strips securing one of said edges of the back panel to the adjacent one of said edges of the front panel, the other of said edges of the back panel being a free edge and being removably held by the adjacent binding and retaining strip so that said free edge of the back panel may be detached from said adjacent binding and retaining strip to enable the back panel to be laid flat upon the front panel and thereby adapt the display device to being stored and shipped flat;
- (F) said back panel having slits extending inwardly from its free edge toward its secured edge to define a bracket forming portion which extends beyond said free edge of the back panel when the panel is flat;
- (G) the back panel having notches opening to said slits near the edge of the panel remote from the inner ends of the slits;
- (H) and the bracket forming portion having notches in the side edges of its free end to interengage with those in the back panel, and thereby connect the free end of the bracket forming portion to the back

5

panel, whereby the bracket forming portion may be shaped as required to support the display device with its front panel substantially upright and resting on one of its said parallel edges.
